UNITED STATES PATENT OFFICE.

EDWIN L. WALTER, OF SCRANTON, PENNSYLVANIA.

COCK OR FAUCET.

SPECIFICATION forming part of Letters Patent No. 769,521, dated September 6, 1904.

Application filed November 5, 1903. Serial No. 179,964. (No model.)

To all whom it may concern:

Be it known that I, EDWIN L. WALTER, a citizen of the United States, residing at Scranton, in the county of Lackawanna and State of Pennsylvania, have invented certain new and useful Improvements in Cocks or Faucets, of which the following is a specification.

In water-controlling fixtures—such as cocks, faucets, and the various types of valves—it is essential where economy in the consumption of water is a factor to construct the same so as to close automatically when no longer required for immediate use, thereby preventing the waste incident to a running stream, as when the cock is left open. Usually self-closing cocks require to be held open, or if provided with means to hold them open said means are either complex or are exposed to the action of the water passing through the cock, hence are soon impaired either by corrosive action or by sediment.

This invention aims to simplify the construction of the type of self-closing cocks, yet combine therewith a time mechanism and means for holding the valve open, said parts being of novel construction and arranged so as not to be in contact with or influenced by the action of the water passing through the cock.

A further purpose of the invention is the utilization of a single spring for seating the valve and operating the movable element of the time mechanism and to devise a construction certain and positive in action, readily accessible for any purpose, not liable to get out of repair, and which will be neat, compact, reliable, and not apt to require frequent attention to maintain it in working condition.

For a full description of the invention and the merits thereof and also to acquire a knowledge of the details of construction of the means for effecting the result reference is to be had to the following description and drawings hereto attached.

While the essential and characteristic features of the invention are susceptible of modification, still the preferred embodiment of the invention is illustrated in the accompanying drawings, in which—

Figure 1 is a vertical central section of a

basin-cock embodying the invention, the valve being closed. Fig. 2 is a view similar to Fig. 1, showing the relation of the parts when the valve is open. Fig. 3 is a view similar to Figs. 1 and 2, showing the arrangement of the parts when the piston or movable element of the time mechanism has reached a point in its return stroke to trip the catch holding the valve open. Fig. 4 is a view similar to Fig. 1 of a flush cock or valve. Fig. 5 is a detail perspective view of the telescoping sections of the valve and operating stems, the parts being separated. Fig. 6 is a perspective view of the guide-sleeve. Fig. 7 is a perspective view of the catch.

Corresponding and like parts are referred to in the following description and indicated in all the views of the drawings by the same reference characters.

The body of the cock or faucet is indicated at 1 and may be of any design or finish, according to the particular use intended and the location of the fixture. When designed for lavatory purposes, the same will be provided with a spout 2; but for flushing purposes the body will be provided with the end 3 for coupling thereto of the flush-pipe (not shown) or rubber tubing. The valve-seat 4 is located at the lower end of the body, and the valve 5 is adapted to close upward thereon and may be of any kind. A plate 6 closes the upper end of the body or casing 1 and is connected thereto in any manner, preferably by means of the tubular section 7, threaded into the body and constituting a box to receive the packing 8, compressed by means of the gland 9, threaded into the part 7. Rims 10 and 11 project from the upper side of the plate 6 and receive the cylinder 12 and sleeve 13, which are threaded thereto. The upper end of the cylinder is closed by the cap 14, provided with the stuffing-box 15, through which the operating-stem 16 passes.

The valve-stem 17 is threaded to the section 18 to admit of lengthening and shortening the stem to insure proper seating of the valve. The section 18 has a close fit in the stuffing-box provided at the lower side of the cap 6 and is provided at its upper end with the tubular section 19, having an inner flange 20 at

its upper end for coöperation with a shoulder 21 at the lower end of the section 22, threaded to the operating-stem 16 and forming, in effect, a part thereof. It will thus be seen that 5 both the operating-stem and the valve-stem involve a sectional construction which have a telescopic relation, the section 22 being slideable within the section 19. The tubular section 19 is provided in a side with a slot 23 and 10 in its upper end with a transverse slot 24 for the purpose presently to be explained.

The piston 25 is secured to the lower end of the section 16 of the operating-stem and comprises upper and lower plates and an interposed packing 26, of rawhide or other flexible material, having its edge portion upwardly deflected. A minute passage 27 extends through the piston and is preferably formed in a plug which is passed through corresponding openings in the component parts of the piston. The cylinder 12 below the piston is filled with any liquid, oil being preferred, and when the piston is depressed or moved downward within the cylinder the liquid passes 25 freely by the piston, due to inward yielding of the outer edge portion of the packing 26, and when the piston moves upward the edge portion of the packing 26 is pressed outward into close contact with the walls of the cylinder, thereby preventing the escape of the liquid thereby and compelling the same to pass through the opening 27, which of necessity requires a longer time for the piston to return to a normal position than required for 30 its depression. The interval of time may be controlled by the size of the opening 27 and the quantity of liquid to pass therethrough. Hence by depressing the piston to a greater or less extent the volume of liquid passing 35 above the same may be controlled, and this is regulated in the present instance by means of the set-nut 28, threaded upon the upper portion of the operating-stem 16, so as to limit the downward movement of the stem by contact with the cap of the stuffing-box 15.

The valve-stem comprising the adjustable sections 17 and 18 is provided with the tubular section 19, with which telescopes the headed or shouldered portion of the operating-stem. A catch 29 is secured to a side of the sleeve 13 and is adapted to engage with the tubular section 19 when depressed, so as to positively hold the valve 5 unseated when the cock or fixture is open. This catch consists, 50 essentially, of a spring provided at its upper end with a stop 30 and a trip 31, the latter having its lower corner beveled, as shown at 32, and of a length to project across the guide-sleeve 13 and tubular section 19 and extend 55 into the path of the head or shoulder 21 at the inner or lower end of the operating-stem when the stop 30 engages with the tubular section 19 in a manner to interlock therewith and hold the same depressed. The trip 31 extends 60 through the slot 33 of the sleeve 13 and through

the slot 23 of the tubular section 19. The stop 30 is beveled at its upper corner and is of greater width than the thickness of trip 31, so as to normally hold the trip 31 out of the path of the head 21 to admit of depressing 70 the piston and operating-stem when using the valve or fixture. After the operating-stem has moved a distance so as to make positive engagement with the valve-stem the latter is depressed and the valve 5 unseated, thereby 75 permitting the water to flow. When the operating-stem engages positively with the valve-stem and both move together, the stop 30 comes into play to make positive engagement with the tubular section 19, so as to hold 80 the valve open at the required point. In order that the valve may be unseated to a greater or less distance, a series of notches 34 are provided in a side of the part 19 near its upper end for the stop 30 to enter, or the part 19 85 may be depressed, so that the stop 30 will engage over the upper end thereof. This occurs when the valve is unseated to secure a stream of maximum size. The initial movement of the operating-stem forces the piston through 90 the liquid contained in the cylinder, and when the operating and valve stems engage, so as to move together, a continued movement of the operating-stem unseats the valve. As the piston is moved within the cylinder a spring 95 35, arranged therein, is compressed, and when the pressure is removed from the operating-stem the spring 35 assumes a normal position and returns the parts to the original position, thereby closing the valve and resetting the 100 working parts. The movement of the piston until the valve begins to leave its seat determines the time during which the cock, faucet, or like fixture remains open, as the movement of the valve-stem is comparatively slight. To 105 obtain a small stream, the valve is opened to a point to permit the catch to engage with the first notch of the series 34. To obtain a larger stream, the valve is opened to a greater distance to permit the catch to engage with the 110 next notch, and so on until the maximum size of stream or flow of water is obtained, when the catch will engage with the last notch of the series or snap over the upper end of the tubular section 19. An interval of time must 115 elapse after the valve has been unseated before the head or shoulder 21 of the operating-stem will engage with the inner shoulder 20 of the part 19 and move the same upward to effect positive seating of the valve 5 and a closing 120 of the cock or faucet. Upon the return of the piston to a normal position and before the latter has reached the shoulder or head 21 it comes in contact with the trip 31 and moves the catch outward, thereby disengaging it 125 from the part 19, which being released moves upward with the operating-stem under the influence of the spring 35, when the parts 21 and 20 engage.

To admit of the valve being unseated, in- 130

terlocking means are provided between the operating and valve stems, the same consisting of a stud 36, projected laterally from the section 22 adjacent to the head or outer shoulder 21. This stud 36 is normally in line with the transverse slot 24 across the upper end of the tubular section 19, so as to pass readily therethrough when the fixture is used to obtain the advantages of the time mechanism. 5
 10 By turning the operating-stem slightly either to the right or to the left the stud 36 is thrown out of register with the slot 34 and in a position to engage with the upper side of the inner flange 20. Hence a slight depression of the operating-stem unseats the valve. To return the operating-stem to a normal position, so as to bring the stud 36 in register with the slot 24, a spring 37 is provided and attached to a side of the section 22 of the operating- 15 stem and passes through the transverse slot 24 adjacent to the vertical slot 23. When the operating-stem is turned either to the right or to the left, the spring 37 is deflected from a normal position, and when the operating- 20 stem is released the spring 37, regaining itself, turns the operating-stem and causes it to assume a normal position. This spring 37 projects from the section 22 and normally acts as a guide to hold the operating and 25 valve stems in a given position, so as to prevent the stud 36 from getting out of line with the slot 24 under normal conditions.

When the invention is applied to the type of cocks or like water-fixtures for use in connection with faucets and like toilet appurtenances requiring to be flushed, the spring 37, stud 36, notches 34, and set-nut 38 may be dispensed with, and it is even contemplated within the purview of the invention under 30 certain conditions to omit the catch, as the friction of the valve-stem and the lower stuffing-box applied to the plate 6 is sufficient to hold the valve 5 unseated during the return travel of the operating stem and piston until 35 the shoulder 21 engages with the inner flange 20 and causes the two parts of the stem to move in unison under the action of the spring 35, so as to seat the valve 5 and shut off the flow of water. 40
 50 Having thus described the invention, what is claimed as new is—
 1. In a self-closing cock, the combination with the body or casing having a valve-seat, a reciprocating valve for closing against said seat, a time mechanism arranged out of contact with and the influence of the liquid passing through the fixture, a stem composed of 45 slidably parts, one carrying the said valve and the other coöperating with the time mechanism, a spring for seating the valve and operating the time mechanism, and a catch coöperating with the inner part of the stem to hold the valve unseated, the parts being combined to admit of opening the valve and setting of

the time mechanism at one sliding movement 65 of the said stem.

2. In a self-closing cock, the combination of the body having a valve-seat, a valve coöperating therewith, a stem comprising inner and outer parts slidably related and adapted to 70 make positive engagement in each direction, a cylinder for containing a medium, a piston connected with the outermost part of said stem and arranged to operate in the cylinder and provided with a small opening to retard the 75 passage of the medium by the piston when returning to a normal position after being actuated, and a catch connected with the cylinder and adapted to engage with the inner part of the stem to hold the valve unseated and adapted to be tripped by the outer part of the stem when reaching the limit of its return movement to permit a quick seating of the valve, substantially as described. 80

3. In combination, a body having a valve-seat, a valve coöperating with said seat to shut off the flow through the body, a cylinder connected with said body and having stuffing-boxes at opposite ends, a stem comprising 85 slidably-related parts arranged to operate in 90 the respective stuffing-boxes of the cylinder, the inner member of the stem carrying the valve and the outer member adapted to receive the force for unseating the valve, interlocking means between the two members of the 95 stem for causing simultaneous movement after the outer member has traveled a predetermined distance, a piston connected with the outermost member of the stem and arranged to operate in the cylinder and having a small 100 opening, and a spring located in the cylinder and normally exerting an outward pressure upon the piston, substantially as set forth. 105

4. In combination, a body provided with a valve-seat, a valve for closing against said seat, a cylinder connected to said body and provided at opposite ends with stuffing-boxes, a valve-stem fitted in the inner stuffing-box, an operating-stem slidable in the outer stuffing-box, telescopic sections forming parts of the 110 respective stems and having a limited movement in each direction, a piston connected to the operating-stem, and a spring arranged within the cylinder and normally exerting an outward pressure upon said piston, substantially as set forth. 115

5. In combination, a body, a reciprocating valve coöperating with a valve-seat of said body, a cylinder connected to the body, but not in communication therewith, a stem composed of slidably-related parts having a limited movement in each direction, a catch for co-operation with the inner part of the stem to hold the valve unseated, and a time mechanism applied to the outer part of the stem to 120 effect a seating of the valve, substantially as set forth. 125

6. In combination, a body, a reciprocating

4. valve coöperating with a valve-seat of said body, a cylinder connected to the body, but not in communication therewith, a stem composed of slidably-related parts having a limited movement in each direction, a catch for coöperation with the inner part of the stem to hold the valve unseated, a time mechanism applied to the outer part of the stem to effect a seating of the valve, and means coöperating with the catch and outermost part of the stem for tripping said catch to effect a release of the innermost part of the stem to permit a seating of the valve as the time mechanism reaches the limit, substantially as specified.
5. In a self-closing cock, the combination with the body or casing having a valve-seat, a reciprocating valve for closing against said seat, a time mechanism arranged out of contact with and the influence of the liquid passing through the fixture, a stem composed of slidable parts, one carrying the said valve and the other coöperating with the time mechanism, a spring for seating the valve and operating the time mechanism, a catch coöperating with the inner part of the stem to hold the valve unseated, and a trip extended from the catch into the path of the outer part of the said stem to be engaged thereby to effect a release of the catch as the time mechanism approaches a normal position.
15. 7. In combination, a body, a reciprocating valve, means for normally tending to automatically seat said valve, a time mechanism, a two-part stem having telescopic connection, one of the parts being tubular and having an inner flange provided with a transverse slot, a stud applied to the opposite part and normally in register with said transverse slot and adapted to effect interlocking connection between the two parts when the outermost part is turned, and means for holding the parts of the stem in a given position, substantially as described.
20. 8. In combination, a body, a reciprocating valve, a tubular section connected with the valve-stem, an operating-stem telescopically connected with said tubular section, a cylinder carried by the body, but not in communication therewith, a piston fitted to the operating-stem and arranged to operate in the cylinder and provided with an opening, a spring normally exerting an outward pressure upon
25. the piston, a catch arranged to engage with the aforesaid tubular section to hold the valve unseated, and means coöperating with the catch and operating-stem to effect a release of the valve as the operating-stem reaches the limit of its outward movement to permit seating of the valve, substantially as set forth.
9. In combination, a body, a reciprocating valve, means for normally tending to automatically seat said valve, a time mechanism, a two-part stem having telescopic connection, one of the parts being tubular and having an inner flange provided with a transverse slot, a stud applied to the opposite part and normally in register with said transverse slot and adapted to effect interlocking connection between the two parts when the outermost part is turned, and means for holding the parts of the stem in a given position, substantially as described.
30. 10. In combination, a body, a reciprocating valve, means for normally tending to automatically seat said valve, a time mechanism, a two-part stem having telescopic connection, one of the parts being tubular and having an inner flange provided with a transverse slot, a stud applied to the opposite part and normally in register with said transverse slot and adapted to effect interlocking connection between the two parts when the outermost part is turned, and a spring attached to the part provided with the stud and fitted into the slot of the tubular part to normally hold the parts in a given position, substantially as specified.
35. In testimony whereof I affix my signature in presence of two witnesses.
